(57) **CLAIM**

An ornamental design for a lightweight wire support, as shown and described.

DESCRIPTION

FIG. 1 is a top, side and front isometric view of my lightweight wire support and showing my design;

FIG. 2 is a top plan view thereof;

FIG. 3 is a front elevational view thereof;

FIG. 4 is a bottom plan view thereof; and,

FIG. 5 is a left side elevational view thereof, the right side elevational view being a mirror image.
